UNITED STATES PATENT OFFICE

133,752

DESIGN FOR A BANDEAUX BRASSIÈRE

Suzanne Redares, North Hollywood, Calif., as signor to Anne Alt, Rolling Hills, Calif.

Application February 18, 1942, Serial No. 105,886

Term of patent 14 years

To all whom it may concern:

Be it known that I, Suzanne Redares, a citizen of the Republic of France, residing at North Hollywood, in the county of Los Angeles, and State of California, have invented a new, original, and ornamental Design for a Bandeaux Brassière, of which the following is a specification, reference being had to the accompanying drawing, forming part thereof,

I claim:

The ornamental design for a bandeaux brassière, as shown.

SUZANNE REDARES.
